UNITED STATES PATENT OFFICE

BENJAMIN HEMERKA, OF SHAMOKIN, PENNSYLVANIA

MUFFLER

Application filed August 27, 1929. Serial No. 388,718.

This invention relates to mufflers for internal combustion engines, and more particularly to devices of this character which are particularly adapted for use in connection with engines having a plurality of radially disposed cylinders although it is to be understood that the device may be associated for use with any other type of engine for which same may be found adapted, and has for one of its objects to provide, in a manner as herein-after set forth, a muffler having mechanical means embodied therein for muffling the exhaust of a radial type internal combustion engine wherein said mechanism means is actuated by the engine upon which the muffler is installed.

Other objects of the invention, are to provide a muffler of the aforementioned character which may be expeditiously installed on an engine, which is strong, durable, simple in construction, efficient in its use, and which may be manufactured at a low cost.

Other objects and advantages of the invention will be apparent from a study of the following specification taken in connection with the accompanying drawings, wherein like characters of reference designate corresponding parts throughout the several views and wherein:

Figure 1 is a front elevation of the muffler showing the same installed on a radial type engine.

Figure 2 is a vertical sectional view of a muffler constructed in accordance with this invention.

Figure 3 is a front elevation of the rotor showing the same removed from the casing.

Figure 4 is a side elevation, partly in section, of the rotor.

Figure 5 is a detail view in perspective of one of the curved blades of the rotor.

Figure 6 is a horizontal sectional view of a portion of the rotor and the casing therefor, said view also showing a portion of an exhaust pipe communicating with said casing.

Figure 7 is a sectional view taken on the line 7-7 of Figure 6 showing the configuration of the exhaust pipe at its point of connection with the rotor casing.

Referring to the drawings in detail, the reference character 1 designates generally an internal combustion engine of the radial cylinder type, 2 indicates the cylinders thereof, and 3 designates the exhaust pipe or conduit leading from said cylinders. The engine 1 is provided with a crank case 4, one end of which is closed by a removable cap 5. An opening 6 is provided centrally in the closure plate 5 for the passage of the engine 60 crank 7, the closure plate 5 being secured to the crank case 4 by means of a plurality of threaded securing elements 8 having securing nuts 9 threaded thereon.

The element 8 may be in the form of headed studs having threaded shanks extending from both sides of the head and this second threaded shank is designated by the reference character 10. A circular bracket 11 is mounted on the crank case 4 concentrically with the 70 crank shaft 7 by means of a plurality of substantially L-shaped apertured brackets 13 which are mounted on the shanks 10 of the securing element 8 and are held thereon by a nut 14.

The circular base or plate 11 is provided with a centrally disposed opening 15 and a bearing box 16 through which the outer end portion of the crank shaft 7 extends. The free end of the crank shaft is provided with 80 a reduced threaded portion 17 upon which a rotor is mounted and secured by means of the nuts 18. The rotor is designated generally by the reference character 19 and comprises a web portion 20 having a hub 21 and an 85 annular rim 22. The rotor further comprises an annulus 23 of greater diameter than the rim 22 and said annulus surrounds said rim in spaced relation thereto.

Interposed between the rim 22 and annulus 90 23 are a plurality of rearwardly curved circumferentially spaced baffle plates or blades 24 which are provided, at their upper and lower edges with right-angular disposed apertured flanges for the passage of securing elements for securing said baffles in position in the rotor. The rotor 19 is closed in a casing 26 which is detachably secured to the marginal portion of the base 11 through the medium of an outwardly turned flange 27 and 100

the securing elements 28. The end wall of the casing 26 is provided with a substantially semi-circular portion which constitutes an annular chamber 29 for the reception of the 5 exhaust gases which pass between the baffle plates or blades 24.

The remaining portion of the end wall of the casing is directed inwardly toward the axis of the rotor, as indicated by the reference character 30.

10 The exhaust pipes 3 are circular in cross section to a point adjacent their connection with the base plate 11, where same assume a polygonal configuration in cross section, as clearly 15 illustrated in Figures 6 and 7 of the drawings and indicated by the reference character 31. A take-off conduit 32 communicates with the annular chamber 29 at any desired point therein for the purpose of permitting the escape of the exhaust gases therefrom.

20 A vertical baffle 33 is positioned in the chamber 29 in front of the intake end of the conduit 32 for the purpose of preventing exhaust gases from the adjacent exhaust pipes from passing directly through the muffler and casing and out through the pipe 32, as will be understood.

25 In use, the muffler functions in the following manner: With the engine in operation, the crank shaft 7 imparts very rapid rotary motion to the rotor 19. Exhaust gases, leaving the cylinder 2 through the exhaust pipe 3 are drawn between the rapidly rotating baffles 30 or plates 24 from between which they merge 35 into the annular chamber 29 and escape through the conduit 32.

30 The rapidly rotating blades cause the sharp and distinct explosion report of each cylinder 40 to be blended into a continuous hum of much less volume than would be the case in mufflers of ordinary construction where no mechanical or moving parts are used. The exhaust pipes 3 are provided with the rectangular ends 31 45 for the purpose of discharging the exhaust gases over the entire length of the baffle plates which are adjacent the exhaust pipe openings into the casing.

50 It is thought that the many advantages of a muffler constructed in accordance with this invention will be readily understood, and although the preferred embodiment of the invention is as illustrated and described, it is to be understood that changes in the details of construction may be had which will fall within the scope of the invention as 55 claimed.

What is claimed is:

60 An apparatus of the character described comprising in combination, an engine having a plurality of radially disposed cylinders and a crank case, a crank shaft extending from said crank case, a casing mounted on the crank case in a manner to rotatably enclose the free end of the crank shaft, exhaust gas

70 conduits communicating with the interior of the casing at its marginal portion and with the cylinders of the engine, a rotor mounted on the free end of the crank shaft and enclosed in the casing, circumferentially spaced baffle plates mounted in the peripheral portion of said rotor and adapted to receive the exhaust gases therebetween, an annular chamber formed in the marginal portion of the casing and adapted to receive exhaust gases 75 from the rotor, an escape conduit connected to said chamber, and a stationary baffle mounted in said chamber in front of the escape conduit.

78 In testimony whereof I affix my signature. so
